UNITED STATES PATENT OFFICE.

HENRY F. TIEDEMANN, OF NEW YORK, N. Y., ASSIGNOR TO THEO. TIEDEMANN & SONS, INC., OF NEW YORK, N. Y., A CORPORATION OF NEW YORK.

MACHINE FOR MAKING SHIRRED RIBBONS.

Application filed October 10, 1925. Serial No. 61,664.

To all whom it may concern:

Be it known that I, HENRY F. TIEDEMANN, a citizen of the United States, and a resident of the city, county, and State of New York, have invented a certain new and useful Improvement in Machines for Making Shirred Ribbons, of which the following is a specification.

This invention relates to a machine for 10 producing shirred ribbons and particularly that type of ribbon which is provided with a center strip or flat tape having shirred strips of ribbon on its opposite faces.

The object of this invention is to provide 15 a machine for sewing together by a single operation the various parts of the strip, that is, the shirred outer faces and the flat center strip so that quantities of this type of ribbon can be very rapidly and expeditiously 20 turned out.

With these objects and such other objects as may hereinafter appear, in view, I have devised the particular arrangement of parts hereinafter set forth and more particularly 25 pointed out in the claims appended hereto.

Reference is to be had to the accompanying drawing, forming a part hereof in which—

Figure 1 is a side elevation of my im- 30 proved mechanism;

Figure 2 is a sectional view on the line 2—2 of Figure 1 looking in the direction of the arrows;

Figure 3 is a perspective view of the guide 35 for the ribbons and tape;

Figure 4 is a plan view of a part of the machine;

Figure 5 is a plan view of the presser foot;

Figure 6 is a sectional view of the same 40 on the line 6—6 of Figure 5 looking in the direction of the arrows;

Figure 7 is a sectional view on the line 7—7 of Figure 5 looking in the direction of the arrows;

Figure 8 is a view of the underside of the 45 presser foot; and

Figure 9 is a plan view of a section of the ribbon, a part of which is shirred in the manner produced by my machine.

Throughout the various views of the drawings, similar reference characters designate 50 similar parts.

In the preferred embodiment my invention, 1 indicates the head of the sewing ma- 55 chine, 2 indicates the presser foot holder

and 3 the needle holder. The needles 4 are carried in a block 5 and a pair of needles are used, the same being spaced apart the correct distance so that they apply spaced lines of stitching as will be hereinafter pointed out.

The presser foot is indicated at 6 and the same is capable of universal adjustment, it being adjustable sideways by means of the bolt 7 and it is adjustable backward and forward by means of the screw 8. The presser foot 6 consists of a central plate 9 having a toe portion 10 which is slotted at 11 and 12 so that the needle holes 13 in the plate 9 are uncovered and free to permit the 70 passage of the needles therethrough. The toe portion 10 has side parts 14 which embrace the sides of the plate 9 and the parts 9 and 10 are adjustable relative to one another by means of set screws 15. 75

It will be noted that the toe portion 10 is provided with a rounded front edge 16, a central groove 17 and spaced faces 18 lying on opposite sides of the groove 17. At 19 is the bed of the machine and this is provided with a removable plate 20, said plate having a plurality of slots 21 through which grippers 22 are movable. The apertures 21 in the plate 20 are located directly below the presser foot so that the grippers 22 may 85 move upward through said apertures 21 and gather the material to be shirred as will be hereinafter pointed out. The plate is provided with needle openings 23 and thread loopers 24 are located below the base of the 90 machine and operate in the conventional manner.

The grippers 22 are actuated in the usual manner by rock shafts 25 and 26 held in brackets 27 and 28 on the underface of the 95 base of the machine.

At 29 is shown the guide for the ribbons and tape which are united together to produce the finished product. Said guide consists of a flat bar 30 to which is secured a 100 flattened tube 31 and a similar flattened tubular guide 32, between which is secured a narrower tubular guide 33, the three guides 31, 32 and 33 being joined together as a unit as clearly indicated in Figure 3. 105

It will be seen that each of said guides may accommodate and permit the passage of a strip of fabric, the upper and lower guides 31 and 32 providing for the passage of the outer shirred ribbons 34 and 35 and the nar- 110

row central guide 33 providing for the passage of the central section of tape 36 which is in the finished product secured between the ribbons 34 and 35.

5 The bar 30, to which the guides 31, 32 and 33 are secured, is slotted as at 37 and 38 to receive screws 39 and 40 which secure the guide in position, the slots permitting adjustment of the guide so that the same may 10 be properly aligned with the pressure foot 6.

From the foregoing, the operation of my improved machine will be readily understood. The three elements which make up the finished shirred ribbon, consisting of the 15 outer shirred strips 34 and 35 and the central flat tape 36 are fed through their respective guides 31, 32 and 33, as is indicated in Figure 1. The three strips of fabric pass together and on top of one another underneath the presser foot 6. As said presser foot is grooved as at 17, it will be seen from 20 Figure 2 that the central tape 36 lies within the groove 17 and does not contact with the presser foot.

25 The underfaces 18 on the part 10 of the presser foot bear down upon the side edges of the two strips 34 and 35 and these two strips at their side edges are gripped between the underfaces 18 of the presser foot 30 and the grippers 22.

The grippers 22 therefore operate with their usual rocking movement and tend to gather the two strips 34 and 35 on the central tape 36, leaving said tape 36 entirely 35 flat and unshirred. The rounded front 16 of the presser foot 6 permits the ready entrance of the three layers of fabric as clearly disclosed in Figure 1.

40 It will be seen that the action of the grippers 22 co-operating with the spaced underfaces on the presser foot 6 readily shifts the outer gathered fabric strips 34 and 35 relative to the central strip 36 so that the gathered effect is produced in said outer strips, leaving the central strip entirely flat and smooth.

A portion of the ribbon in its gathered 45 form is shown in the upper part of Figure 9.

From the foregoing, it is obvious that my 50 invention is not to be restricted to the exact embodiment shown but is broad enough to cover all structures coming within the scope of the annexed claims.

What I claim is:

55 1. A machine of the class described having a guide provided with a plurality of

separate guide-ways for supplying a pair of ribbons and a narrower tape between the ribbons, a presser foot under which said ribbons and tape are moved, gripping means 60 operative under said foot for engaging with parts of the ribbon and gathering the same independently of the tape, and a groove in the underface of the foot in which the tape is located during the gathering operation. 65

2. A machine of the class described comprising a guide having three tubular guide-ways through which a tape and a pair of ribbons on opposite sides of said tape are passed, a presser foot under which said tape and ribbons are passed, gripping and gathering means operative beneath said foot, said gripping and gathering means being adapted to engage the ribbons near their longitudinal edges, and a groove in the 70 underface of the foot in which the tape lies so that the same is not engaged by the gripping means.

3. A machine of the class described having a guide provided with three independent 80 grooves through which a pair of ribbons with a tape between them is fed, a presser foot under which said ribbons and tape are fed, spaced gripping faces on the under side of said foot, gathering means movable 85 beneath the presser foot, and adapted to grip the ribbons near their edges, the tape being movable between the gripping faces on the foot so that said tape is not gripped by the gathering means. 90

4. A machine of the class described having a guide provided with three channels located above one another and through which a pair of ribbons and a tape are adapted to be fed, the wider ribbons passing through the upper and lower channels and the narrower tape through the central channel, a foot under which the tape and ribbons are fed, a groove in the under face of the foot through which the tape passes and spaced faces on opposite sides of the groove against which side portions of both ribbons bear, and gathering means movable below the foot and gripping the side portions of the ribbons against the under face of the foot and gathering both of said ribbons independently of the tape located between them. 95

100 Signed at the city, county and State of New York, this 8th day of October, 1925.

HENRY F. TIEDEMANN.
